UNITED STATES PATENT OFFICE.

JOHN W. W. CUMMING, OF THE UNITED STATES NAVY.

MULTIPLE GRINDING-MACHINE.

1,217,417.

Specification of Letters Patent. Patented Feb. 27, 1917.

Application filed October 25, 1916. Serial No. 127,620.

To all whom it may concern:

Be it known that I, JOHN W. W. CUMMING, a lieutenant in the United States Navy, a citizen of the United States, at 5 present attached to the U. S. S. *Prometheus*, have invented certain new and useful Improvements in Multiple Grinding-Machines; and I do hereby declare the following to be a full, clear, and exact description of the invention, such as will enable others skilled in the art to which it appertains to make and use the same.

This invention relates to grinding machines of the type adapted to grind the ends 15 of boiler tubes or other pipes preparatory to flanging the same, and has for its object to provide a machine of this character which will be more simple in construction, more efficient in action and less costly to 20 manufacture than those heretofore proposed.

With these and other objects in view the invention consists in the novel details of construction and combinations of parts more 25 fully hereinafter disclosed and particularly pointed out in the claims.

Referring to the accompanying drawings forming a part of this specification in which like numerals designate like parts in all the 30 views:—

Figure 1 is a central longitudinal sectional view, partly in elevation, of one form 35 of machine made in accordance with this invention;

Fig. 2 is an enlarged detail sectional view, taken on the line 2—2 of Fig. 1, and looking in the direction of the arrows;

Fig. 3 is an end elevational view of the parts shown in Fig. 1, as seen from the 40 right of said figure;

Fig. 4 is a view similar to Fig. 3, but looking from the left of Fig. 1; and

Fig. 5 is a view similar to Fig. 3, but showing the parts in slightly different positions.

1 indicates a bed or base provided with the grooves 2 in which fit the projections 3 of the slidible member 4. Rollers or other antifriction devices such as 5 are provided 50 between the member 4 and the base 1 to facilitate the easy movement of the said member, as will presently appear.

The member 4 is provided with two upwardly extending arms 6 and 7, carrying respectively at their upper extremities the 55 bearings 8 and 9, see Figs. 1 and 4. Jour-

naled in the said bearing 8 is a shaft 10, carrying the gear 11 and the elongated gear 12, both rigidly secured thereto, see Figs. 1 and 4. The said bearing 8 is also extended 60 as at 13, Fig. 4, to accommodate a power shaft 14 carrying the gear 15 meshing with the gear 12, as shown.

Mesning with the gear 11 is a gear 16 rigidly mounted on a stub shaft 17, one 65 end of which is journaled in an eccentric bearing block 18, rotatably mounted in the arm 6. The other end of the said shaft 17 is journaled in a companion eccentric bearing block 19 carried by the arm 7, and the 70 said shaft further has rigidly mounted on this said end a gear 20 meshing with a gear 21, all as will be clear from Fig. 1.

The said gear 21 is rigidly mounted on one end of a sleeve 22, journaled in the 75 bearing 9 and surrounding the shaft 10; and the said sleeve is provided at its other end with a flange 23, carrying one or more spindles 24, each surrounded by a sleeve 25, for a purpose to be more fully disclosed below.

Loosely mounted on the sleeve 22, adjacent the flange 23 is a wheel or disk-like member 26, provided with one or more slots 27. A stud 28 passes through each of said 85 slots and engages the rear wall of a hollow block like member 29, thereby fastening the said members to the face of the said disk 26, but at the same time, permitting them to slide over said face in a manner to be more 90 fully hereinafter described.

The said members 29 are preferably hollow, as indicated in Figs. 1 and 2, and are provided in the wall opposite to that engaged by the studs 28, with a slot 30. A 95 block 31 is slidably mounted in the interior of said hollow members 29 and said blocks are provided with extensions 32 entering the said slots 30, all as will be clear from the drawings. Each block 31 is bored to accommodate a threaded spindle 33, which passes through the head 34 of the member 29, and is journaled in the wall 35 thereof. The bore of the block 31 is larger than the diameter of the said spindle, thus permitting 100 the said block to slide freely along the latter. A pair of threaded nuts 36 and 37 are also mounted within each member 29, engaging the spindles 33, one on each side of each block 31, and a spring 38 is interposed 105 between each nut 36 and the said blocks 31, as shown.

Screw threaded or otherwise secured to the extension 32 of the block 31 is a stub shaft 39, upon which is mounted a pulley 40, having a sleeve 41 carrying at its end the abrasive wheel 42.

5 The members 29 each have an extension or ear 43 provided with an opening adapted to accommodate the sleeve 25 surrounding the spindle 24, around which the said members 29 pivot, as will be presently disclosed.

10 The sleeve 25 carries on one side of the said ear 43, a gear 45, meshing with a gear 46 mounted on the shaft 10, while on the other side of the said ear 43, the sleeve carries a pulley 47 around which passes a belt or other connection 48, which also engages the pulley 40, see Figs. 1, 3 and 5. A suitable belt-tightener, comprising the lug 20 49 through which passes the rod 50, having the bent end 51 upon which is mounted the roller 52, controlled by the spring 53 and the nut 54 is provided on each of the members 29 to adjust the tension of the belts 48.

25 Loosely mounted on the sleeve 22 and connected to the disk 26 in any suitable manner, is the lever 55, having the pivoted member 56, joined as by the connecting rod 57 to the latch 58, controlled by the spring 59. The 30 said latch 58 is adapted to engage the teeth of a gear 60 rigidly mounted on the said sleeve 22, see Figs. 1 and 4.

Rigid with the base 1 is the lug 65, through which passes the threaded shaft 66, 35 secured against relative longitudinal movement in the arm 7, and provided at its end with the star wheel 67. The said star wheel is located in the path of the actuating finger 68, adjustably secured to the disk 26, so 40 that upon the rotation of the said disk the said star wheel together with its screw shaft 66 will be rotated, and the entire mechanism moved longitudinally of the bed 1, the direction depending upon whether the finger 45 68 engages the wheel 67 at the top or at the bottom.

The pipe 70 or other articles to be ground are held by means not shown in such position that their axes will be in prolongation 50 of the axis of the shaft 10. The abrading wheel, or wheels 42, being then brought into contact with the outer or inner surfaces of said pipe as may be desired.

The operation of the machine will be clear 55 from the foregoing, but may be briefly summarized as follows:—Supposing the parts to be in the positions shown in Fig. 3 and a pipe such as 70, for example has been suitably brought into the position shown, with 60 its extreme end in contact with the peripheries of the said abrasive wheels 42.

Power is now transmitted through the shaft 14 to the gear 15, and from said gear 15 to the elongated gear 12 which being rigid 65 with the driving shaft 10, turns the same to-

gether with the gears 11 and 46 rigid with said shaft 10. The turning of the gear 46 turns the several gears 45 and said gears 45 turn the sleeves 25, which rotate the pulleys 47, thus transmitting power through the 7 belts 48 to the pulleys 40, which turn the sleeves 41 carrying the abrading wheels 42. The turning of the said shaft 10 and the said gear 11, also turns the gear 16 rigid with the shaft 17 and the latter turns the gear 20 75 meshing with the gear 21, which imparts rotation to the sleeve 22, which latter imparts rotation to the gear 60 rigid therewith. The rotation of the gear 60 imparts rotation to the spring controlled dog 58, and to the arm 80 or lever 55 rigid with said dog. The said arm or lever 55 is connected with the disk or wheel 26 by any suitable means, as for example, by the dog 56 so that, as the said sleeve 22 rotates the said disk 26 is also rotated and causes, in turning, each of the abrading wheels 42 to revolve around the pipe 70 being ground through the connections 31 and 39 as shown.

In addition to the above, the turning of 90 the said sleeve 22 causes the flange 23 thereof to turn and to carry with it the spindles 24 on which are mounted the pulleys 47, so that the pulleys rotating the abrading wheels on their axes revolve around the axis of the 95 pipe 70 along with the abrading wheels 42. Of course, it is obvious that a single abrading wheel 42 may be employed or any suitable number of abrading wheels may be employed. Each abrading wheel is radially adjustable independently of the others through the screw means 33, nuts 36 and 37, etc., all as will be clear from the disclosure above.

The members 33 are conveniently held in position by the lock nuts 33', as will be 105 readily understood.

In addition to the independent radial adjustment of the said abrading wheels 42, they may be simultaneously radially adjusted either toward or from the axis of the 110 pipe 70 in the manner now to be described.

Referring to Fig. 3, it is evident that the pipe 70 being removed, each abrading wheel 42 may be turned on its corresponding spindle 24 as a center from the position shown in 115 said Fig. 3 to the position shown in Fig. 5, so that each abrading wheel may be independently adjusted to pipes of different diameters, and when they have been once so adjusted the turning of the disk or wheel 26 120 on the shaft 10, as a center, will further carry all of the abrading wheels 42 toward or from said shaft 10, according to the direction in which said wheel or disk 26 is rotated. During such turning movement of 125 the wheel 26, to still further simultaneously radially move the abrading wheels 42, it of course, is necessary that the flange 23 and the sleeve 22 remain stationary. In order that this may be accomplished, the lever 55 may

be disengaged from the said wheel 26 as by turning the dog 56 on its pivot 75, and then turning the said wheel 26 independently of said lever 55 and sleeve 22, or of course, the 5 disengagement of the wheel 26 from the sleeve 22, may be accomplished by raising the dog 58 out of contact with the gear 60 through the dog 56 and rod 57, whereupon both the lever 55 and wheel 26 will turn together and all the abrading wheels 42 thus 10 brought to a new radial position with respect to the shaft 10, and locked in said new position by the reengagement of the dog 58 with the gear 62.

15 The abrading wheels 42 being thus ad-
justed to the particular diameter of the pipe
or rod being ground, the said wheels 42 are
then continuously rotated on their indi-
vidual axes 39 as well as continuously re-
20 volved around the said pipe or other article
70 in the manner above disclosed. At each
revolution of the wheel 26, the pin or finger
68 strikes the star wheel 67, turns the screw
shaft 66 and feeds the entire mechanism in-
25 cluding the abrading wheels axially of the
article 70 being ground, all in a manner that
will be clearly understood. It is sometimes
desirable to turn the mechanism around the
axis 10 by hand and at the same time ac-
30 complish the feeding of the said abrading
wheels 42 by hand. In such cases the lever
80, see Fig. 4, may be turned by hand thus
revolving the eccentrics 18 and 19 to such a
position that the gears 16 and 20 will be
35 disengaged from their respective gears 11
and 21, so that the sleeve 22 may turn in-
dependently of the power shaft 14.

When the above disengagement of gears has been accomplished then the wheel 26 may be freely revolved by hand, and with said wheel, of course, will revolve the abrading wheels 42 and their associated mechanism, while the pin 68 and star wheel 67 will accomplish the axial feeding of the said abrading wheels in the manner above disclosed.

It will thus be seen that the mechanism now described provides a rotating disk or head 26 together with means adapted to 50 rotate the same, consisting of the sleeve 22 and the gears 15, 12, 11, 16, shaft 17 and gears 20 and 21; that the said disk or head 26 is loosely mounted on said sleeve 22 but is readily connected to and disconnected 55 from said sleeve by means of the latch 58, gear 60 and associated parts. Said head is provided with a plurality of slots 27 and is associated with a plurality of members 29 pivoted on the spindles 24, and said members 60 29 are provided with the slidable blocks 31, carrying the spindles or stub shaft 39 and sleeves 41 on which are mounted the abrading or polishing wheels 42.

It results from this that when the head
65 26 is revolved independently of the sleeve

22 all of the members 29 are canted or moved from their radial positions shown in Fig. 3 to their inclined positions shown in Fig. 5, so that the abrading wheels 42 are simultaneously adjusted to or from a fixed axis such that of the rotating shaft 10. In addition to the above simultaneous adjustment of the wheels 42, it is evident that each wheel may be radially and independently adjusted by means of the screw 33 and block 31. It is further evident that the flange 23 of the sleeve 22 carries an independent power transmitting means consisting of the pulley 47 for rotating its associated wheel 42 through the belt 48, pulley 40 and sleeve 41. 70 75 80

It thus follows that this invention provides two independent radial adjustments of the wheels 42 and that the said wheels 42 may be simultaneously radially adjusted while the individual wheels are being rotated on their own axis. 85

It is obvious that those skilled in the art may vary the details of the construction as well as the arrangement of parts without departing from the spirit of the invention, and therefore, it is not desired to be limited to the above disclosure except as may be required by the claims.

What is claimed is:—

1. In a machine of the class described the combination of a power shaft; a rotatable head; connections between said shaft and head for rotating the latter; an abrading wheel; slidably adjustable connections comprising a radially movable block between said head and wheel; and means comprising a belt and a pair of pulleys for rotating said wheel on its axis independently of said head, substantially as described. 100

2. In a machine of the class described the combination of a power shaft; a rotatable head; connections between said shaft and head for rotating the latter; an abrading wheel; slidably adjustable connections comprising a screw controlled radially movable block between said head and wheel; means comprising a belt and a pair of pulleys for rotating said wheel on its axis independently of said head; and means for revolving around a fixed axis said last named means together with said wheel while the latter is rotating, substantially as described. 110 115

3. In a grinding machine the combination of a grinding wheel; a rotatable head; adjustable connections between said wheel and head by which said wheel may be radially moved toward and from a fixed axis; additional means by which said wheel may be moved toward and from said axis; means for rotating said wheel on its axis; and means for rotating said head and thereby revolving said wheel around said fixed axis, substantially as described. 120

125

4. In a grinding machine the combination of 180

- tion of a rotatable shaft; a rotatable sleeve carried by said shaft; a power transmitting means carried by said sleeve and adapted to revolve around the axis of said shaft; a rotatable head mounted on and revoluble around said sleeve; an abrading wheel carried by said head; a radially movable block mounted in said head for adjusting said wheel; and connections between said power transmitting means and said wheel for rotating the latter on its axis, substantially as described.
5. In a grinding machine the combination of a rotatable shaft; a rotatable sleeve carried by said shaft; connections between said 10 shaft and sleeve by which the latter is rotated from the former; a power transmitting means carried by said sleeve and adapted to revolve around the axis of said shaft; a rotatable head loosely mounted on said sleeve; means adapted to readily connect and disconnect said sleeve and head; an abrading wheel carried by said head; and connections between said power transmitting means and said wheel for rotating the latter on its axis, 15 substantially as described.
6. In a grinding and polishing machine the combination of a power shaft; a rotatable shaft; means for rotating said last named shaft from said power shaft; a sleeve 20 mounted on said rotatable shaft; means for rotating said sleeve; a head loosely mounted on said sleeve; means for readily connecting and disconnecting said head and sleeve; a plurality of abrading disks carried by said head; a plurality of power transmitting means carried by said sleeve one for each disk; and a connection between each power transmitting means and disk for rotating the latter on its axis, substantially as described.
7. In a grinding and polishing machine the combination of a plurality of abrading disks angularly disposed with relation to each other; means for independently adjusting each disk toward and from a fixed 25 axis; and means for adjusting all of said disks simultaneously toward and from said axis.
8. In a grinding and polishing machine the combination of a plurality of abrading disks angularly disposed with relation to each other; means for independently adjusting each disk toward and from a fixed axis; means for adjusting all of said disks 30 simultaneously toward and from said axis;

independent means for rotating each disk on its own axis; and means for simultaneously revolving all said disks around said fixed axis, substantially as described.

9. In a grinding and polishing machine 60 the combination of a rotating means; a rotatable head loosely mounted on said means; a member mounted on said head and pivotally connected to said rotating means; an abrading wheel carried by said member; and means for readily connecting and disconnecting said head and rotating means whereby said head may be independently rotated when disconnected and said wheel radially adjusted to and from a fixed axis, substantially as described.

10. In a grinding and polishing machine the combination of a rotating means; a rotatable head loosely mounted on said rotating means; a member movably secured to 75 said head and pivotally connected to said rotating means; an abrading wheel carried by said member; means for adjusting said wheel relatively to said member and toward and from a fixed axis; and means for readily connecting and disconnecting said head and rotating means, whereby said head may be independently rotated when disconnected to independently radially adjust said wheel to and from said fixed axis, substantially as 80 described.

11. In a grinding and polishing machine the combination of a rotating means; a rotatable head loosely mounted on said rotating means; a hollow member movably secured to said head and pivotally connected to 90 said rotating means; a block slidably mounted in said hollow member; an abrading wheel carried by said block; means adapted to move said block and wheel relatively to said member; means including a belt adapted to revolve said wheel upon its axis; means adapted to control the tension of said belt; and means for readily connecting and disconnecting said head and rotating means whereby said head may be independently rotated when disconnected and said wheel radially adjusted to and from a 95 fixed axis, substantially as described.

In testimony whereof I affix my signature, 105 in presence of two witnesses.

JOHN W. W. CUMMING.
